In Germany June 20, 1935

6 Claims. (Cl. 250—27.5)

The present invention relates to electron tubes for handling—i. e., generating, amplifying, or receiving—ultra-high-frequency oscillations, and particularly to those with a resonator formed as a chamber, as are for example those forming the subject-matter of Patent No. 2,138,233, issued Aug. 30, 1938.

The present invention has for object in particular chiefly to improve these tubes in such a manner that the vacuum and current supplying conditions are substantially improved.

According to the invention there is attached to the body that bounds the chamber serving as a resonator a second chamber which has metallically conductive walls and which can be rendered dissonant in relation to the first chamber. This step is capable of bringing with it advantages of different kinds. If, for example, the second chamber is arranged in such a manner that the leads pertaining to the electrodes of the tube extend through this chamber there may be thus prevented a loss of oscillation energy that might be led away out of the resonator casing through the leads.

When, as may be advantageous in many cases, the chamber, which is hereinafter referred to as the dissonant chamber, is pumped up to a high vacuum, like the resonator chamber itself, with which it is in communication, the glass fusion joints on the walls bounding the resonator chamber may be omitted. The hollow body bounding the resonator may then be made of any desired metal, in particular of a metal of high conductivity as regards current and heat for the purpose of conducting away at permissibly high temperatures of the electrodes the lost energy liberated at the electrodes. The parts of the walls of the dissonant chamber provided with current through-ducts and bounding the external chamber may then be advantageously made of a metal, especially a metal that can be well fused with glass, for example of nickel-iron, chromium-iron, chromium-nickel, etc. The distance apart of the two walls having lead through-ducts may be made equal to the quarter wave length or an odd multiple thereof and in this way there may be produced an optimum dissonance of the chamber and the led-through sections of the leads.

Fig. 1 shows a constructional example of a tube in which a vessel serving as a dissonant chamber is so annexed to the body bounding the chamber serving as a resonator that the leads pertaining to the electrodes extend through the annexed chamber.

Figs. 2 to 5 show constructional examples in

which the body bounding the chamber serving as a resonator is provided wholly in a metal vacuum vessel.

In Fig. 1 the hollow body bounding the resonator consists of the vessel-shaped and cylindrical external conductor 1 and the internal conductor 2, 2' co-axial therewith which together form a concentric Lecher system of the length $\lambda/2$. The lower end of this concentric Lecher system is closed by the wall 3. From the upper end extends an energy conducting device of the length $\lambda/4$, which forms an extension of and is concentric with the external and internal conductors and consists of an internal conductor 4 and an external conductor 5. The internal conductor 4 merges without cross-sectional variation into the $\lambda/4$ antenna 6, and to the external conductor 5 there is connected a metal plate 7 which is at right angles to the axis of the tube and which serves for the capacitive transmission of the antenna current. The middle portion of the internal conductor 2 is formed as a grid 8, which contains co-axially in its interior a hair-pin-shaped cathode 9. Between the external conductor 1 and the internal conductor 2 there is a cylindrical electrode 10, which is supported against, so as to be insulated from, the external conductor 1 by insulators 11. The electrode 10 divides the toroidal space between the conductors 1 and 2 into two chambers—namely, the resonator chamber proper between the internal conductor 2, 8, 2' and the electrode 10 and a chamber serving as a short-circuit condenser and located between the electrode 10 and the external conductor 1.

In the case of suitable potentials, particularly in the case of a high positive potential at the grid 8 and a negative bias at the enclosed electrode 10, and in the case of suitable electron emission of the hot cathode, the toroidal chamber produces oscillations. In the middle portion of the chamber there is formed a potential anti-node and at the upper and lower ends there are formed potential nodes of the oscillations. The lead 12 connected to the enclosed electrode 10 and the lead 13 connected to the cathode 9 extend through and are insulated from the wall 3 of the chamber resonator. For the purpose of avoiding losses by conduction along these leads there is connected to the lower end co-axially with the hollow body 1 containing the resonator a further cylindrical hollow body 14 of the length $\lambda/4$ through which the leads 12, 13 extend axially. The lower end surface 14, which is preferably of nickel iron or chromium-iron, is provided with openings which

are closed by glass beads 18. By means of these glass beads the leads 12 and 13 are insulated where they extend through the wall 15. The through-passage places in the wall 3 need not therefore be vacuum-tight. When the internal conductor 2 and the wall 3 are made of a metal of good conductivity, for example copper or silver, the heat produced at the biased grid can be conducted away at allowably high temperatures at the electrodes to the external conductor of the tube and radiated away by this in consequence of its great surface.

The hollow body bounding the resonator consists in Fig. 2 of a vessel-shaped and cylindrical external conductor 21 and the internal conductor 22 co-axial therewith, which form a concentric Lecher system of the length $\lambda/2$. The external and internal conductors are connected together galvanically and thermally at the lower end by the wall 28. To the upper end there adjoins an energy conducting device forming an extension of the external and internal conductors of the length $\lambda/4$, consisting of an internal conductor 24 and an external conductor 25. The internal conductor 24 merges into the $\lambda/4$ antenna 26, and the external conductor is connected with the wall 27 of the vacuum vessel, which, together with the ring 28, forms a plate at right angles to the axis of the tube for the capacitive transmission of the antenna current. The middle portion of the internal conductor 22 is formed as a grid 29 which contains co-axially in its interior a hairpin-shaped cathode 30. Between the external conductor 21 and the internal conductor 22 there is a cylindrical electrode 31, which is supported against, so as to be insulated from, the external conductor 21 by insulators 32. The toroidal chamber bounded by the internal conductor 22 and the electrode 31 produces oscillations particularly in braking field connection.

This chamber resonator is placed in a vacuum vessel of metal. For simplicity of manufacture this vacuum vessel is made cylindrical and co-axial with the chamber resonator. The peripheral portion 33 is made for example of iron. Since the upper end surface 27 of the vacuum vessel serves by means of a glass fusion joint 34 for the closing of the annular gap of the high-frequency conductors 24, 25, it consists of a nickel-iron, chromium-iron or chromium-nickel alloy. The internal conductor 24 of the high-frequency conductors or the antenna 26 must likewise consist of suitable material at the place of fusion. Also the lower end surface 35, which is traversed by the leads 36, 37 for supplying the enclosed electrode 31 and the cathode 30, is made of a metal alloy that is capable of being fused with glass in a vacuum-tight manner. The conductors bounding the chamber resonator consist of copper or silver. For the purpose of transferring to the vacuum vessel the heat produced at the grid 29, the chamber resonator is provided at its lower end with a disk-like projection 38 which makes a good thermic connection between the resonator casing and the vacuum vessel. This disk-like projection serves at the same time for supporting the resonator casing in the vacuum vessel. Further there are divided off by it within the vacuum vessel two chambers 39, 40, which may be advantageously employed for the introduction of the leads and for the vaporization of the getter materials. The length of the cylindrical chamber 39, which is traversed by the leads 36, 37, is advantageously made equal to the quarter wave length or an odd multiple thereof, whereby the

leads are given the optimum dissonance. Now in order that all three chambers may be pumped simultaneously to a high vacuum, the annular body 38 is provided with holes 41 and the resonator casing with holes 42. The short tube 43 communicating with the gettering chamber serves for connecting the tube with a high-vacuum pump and for closing the tube by fusion.

Fig. 3 shows in longitudinal section a constructional example that is quite similar to that of Fig. 2 but is intended for producing oscillations in the magnetron connection.

The resonator chamber is in this case also bounded by a concentric and cylindrical Lecher system of the length $\lambda/2$, consisting of an external conductor 44 and an internal conductor 45, 45'. The internal and external conductors are galvanically connected together at their lower end and merge at their upper end into the concentric high-frequency conducting device of the length $\lambda/4$ consisting of the internal conductor 44 and the external conductor 25. To the internal conductor 44 there is again connected the antenna 26 and the external conductor 25 is connected with the metal plate 27, which, together with the annular disk 28, forms the counterpoise to the antenna 26. The electrode system serving for the production of oscillations consists of the hairpin-shaped cathode 47 and a four-part split anode, of which the segments 48, 48', and 49 are shown in the figure. The anode segments 48 and 48' are connected with the casing 44 through connecting parts 50, 50' of pole-shoe shape and the two other anode segments are connected at both ends to the conductors 45, 45'. The field coil 51 serves for producing the co-axial magnetic field.

As a vacuum vessel there serves a cylindrical tube 38 of non-magnetic material, as for example chrome-nickel. The tube is closed at the upper and lower ends by chromium-iron, nickel-iron, or chromium nickel plates 35 and 27. The upper plate 27 carries the glass fusion joint 34 and the lower plate carries by vacuum-tight glass fusion joints 34' the conductors 36, 37 leading to the cathode 47 and to a controlling electrode 47' between the two cathode wires. In this case also a good thermic connection between the resonator casing and the vacuum vessel is made by the disk-like projections 38 and 38'. Furthermore, by the two walls 46 and 35 there is bounded a cylindrical chamber 39 which is dissonant in relation to the proper frequency of the resonator. The chamber 40' substantially surrounding the concentric high-frequency conducting device may be used in a manner corresponding to that of the chamber 40 for the vaporization of getter materials. The chambers bounded by the two metal hollow bodies are connected together by the passages 41' and 42'. The short tube 43 serves again for the connection to the vacuum pump and for the closing of the tube by fusion.

Figs. 4 and 5 show constructional examples of electron tubes with a chamber resonator and a special vacuum vessel, in which a fine adjustment of the proper frequency of the resonator is made possible. Fig. 4 shows a constructional example corresponding to Fig. 2 for the production of oscillations of the resonator in the braking field connection. Fig. 5 shows a constructional example corresponding to Fig. 3 for the production of oscillations in the magnetron connection.

In the case of the example shown in Fig. 4 the vacuum vessel and the resonator casing consist in each case of two sections, which are con-

nected together by yielding wall parts 52 and 53. The upper section of the vacuum vessel 54 is connected rigidly with the upper part 55 of the resonator vessel through the metal plate 27. The lower section 54' of the vacuum vessel is likewise connected with the lower section 55' of the resonator casing. The internal conductor 24 rigidly connected at the upper end with the plate 27 by the glass fusion joint 34 is provided with a 5
trombone telescopic device 56 for the purpose of allowing relative movement of the two sections of the resonator. For the same purpose also the electrode 31, which is completely enclosed by the resonator casing 55, 55' and the internal conductor 10 22, is provided with milled recesses 51, into which the upper insulators 32 can move in the direction of the axis of the tube. For adjusting the resonator there serves a micrometer device which consists essentially of a screw-thread 58 15 on the lower section of the vacuum vessel and a co-axial cylinder 59 which is provided with a counter-thread and which engages by means of guides 60 a ring 61 rigidly connected with the upper section of the vacuum vessel. When this 20 cylindrical part 59 is rotated, the two sections of the vacuum vessel 54, 54' execute relative movements in the direction of the axis of the tube and on account of the rigid connexions of the parts 55, 55' of the casing with one of the 25 sections of the vacuum vessel the parts of the casing execute the same movement. The lower end of the vacuum vessel is closed by a plate 35 of nickel-iron, chromium-iron, or chromium-nickel which is distant $\lambda/4$ from the bottom of 30 the resonator casing and contains the through-ducts for the leads 36, 37 pertaining to the enclosed electrode 31 and the cathode 29. The annular part 38 serves in this case also for producing an intimate thermic contact between the 35 resonator casing and the vacuum vessel. It divides the space between the chamber resonator and the vacuum vessel into the two chambers 39 and 40.

For the vaporization of getter materials in 45 the chamber 40 there serves the heating body 62, one pole of which is connected with the resonator casing whilst the other pole extends through and is insulated from the annular body 38 and also extends through the wall of the dissonant chamber 39 and is insulated therefrom by the vacuum fusion joint 63. Owing to the 50 conductive connection between the resonator casing and the vacuum vessel, the heating body may be connected by one pole. If, now, it is desired to vaporize the getter material during 55 the making of the tube, a corresponding potential is applied between the vacuum vessel and the lead 64 pertaining to the heating body. This lead 64 may then be used later during the working 60 of the tube for applying a suitable potential to the resonator casing and consequently the grid electrode. In consequence of the relatively small current required for the working of the tube, the resistance of the coil 62 plays no part, so that 65 the heating body 62 is not heated at all. In this way special leads for the heating body are avoided.

Fig. 5 shows finally a tube with an adjustable resonator according to Fig. 3 for producing oscillations in the magnetron connection. For the 70 purpose of effecting the fine adjustment of the resonator, the vacuum vessel, and the resonator casing, consist each of two sections that are adjustable in relation to each other. The two sections of the vacuum vessel are again connected

together in a vacuum-tight manner by means of a yielding wall 52. This yielding wall is provided at the upper end of the resonator in order to enable the magnet or the magnetic field coil required for the production of the co-axial magnetic field to be placed close to the tube. The resonator casing consists of the two parts 55 and 55' for the purpose of varying the length of the $\lambda/2$ resonator. The cylindrical part 55 consists substantially of the external conductor of the resonator and the part 66 of the external conductor of the high frequency conducting device. The lower end of the part 66 terminates in the piston-like part 67, which is movable in the external conductor 65 in the longitudinal direction. For the purpose of the adjustment of the internal conductor of the high-frequency conducting device between the chamber resonator and the antenna the internal conductor is provided with a trombone telescopic device 56 20 in the neighbourhood of the potential anti-node of the high-frequency conducting device, as in the case of the example shown in Fig. 4. The micrometer device is made quite correspondingly and is placed at the upper end of the tube in 25 view of the necessary auxiliary magnetic field. The lower section of the vacuum vessel carries at the upper end a screw-thread 58. The annular body 59 provided with a counter-thread engages here the lower surface of the metal plate 30 28 and allows relative movement of the two tube sections in the direction of the axis of the tube.

For the purpose of producing the auxiliary magnetic field co-axial with the tube there is used in the example shown a tubular magnet 68 magnetized in the longitudinal direction. For the purpose of avoiding useless leakage fields, the distance between the vacuum vessel and the resonator casing is made only very small so that this chamber is not suitable for the vaporization of 40 getter materials. The heating body 62 is therefore provided in a special vaporizing chamber 40', which adjoins the lower end of the resonator casing. This heating body is again connected by one pole with the resonator casing, whilst the 45 other pole extends out through the wall of the vaporizing chamber and is insulated therefrom by the vacuum fusion joint 63'. As in the case of the preceding examples, the other leads pertaining to the electrodes in the interior of the 50 resonator casing extend also in this case through a special dissonant chamber 39'.

For the purpose of varying the strength of the field of the permanent auxiliary magnet 68, the lower portion of the tube is provided with a 55 supporting body 69, which carries a variable yoke in the form of a soft-iron tube 70. The supporting body and the yoke are provided with screw-threads. When the yoke 70 is rotated, it moves in the direction of the axis of the tube. It can 60 consequently be moved more or less far over the magnet 68, and thus there may be produced a short-circuit parallel to the field in the interior of the annular magnet by means of which the strength of the magnetic field can be adjusted 65 suitably for the production of oscillations in the tube.

What we claim is:

1. An ultra high frequency electron tube comprising a metallic envelope housing a set of electrodes including a thermionic cathode, said electrodes and envelope forming an oscillatory circuit, an extension of said envelope forming beyond the region housing said set of electrodes a chamber having a length equal to an odd multiple 75

- of the quarter wave length of the length to be generated, and leads for said electrodes extending substantially axially of said envelope and through said chamber.
2. An ultra high frequency electron tube comprising a metallic envelope housing a set of electrodes including a thermionic cathode, said electrodes and envelope forming an oscillatory circuit, an extension of said envelope forming beyond the region housing said set of electrodes a chamber having a length equal to an odd multiple of the quarter wave length of the length to be generated, and leads for said electrodes extending substantially axially of said envelope and through said chamber, the region of the tube housing said set of electrodes and the chamber being evacuated.
3. An ultra high frequency electron tube comprising a metallic envelope housing a set of electrodes including a thermionic cathode, said electrodes and envelope forming an oscillatory circuit, an extension of said envelope forming beyond the region housing said set of electrodes a chamber having a length equal to an odd multiple of the quarter wave length of the length to be generated, and leads for said electrodes extending substantially axially of said envelope and through said chamber, the region of said tube housing said set of electrodes and the chamber being in communication and being evacuated.
4. An ultra high frequency electron tube comprising a metallic envelope housing a set of electrodes including a thermionic cathode, said electrodes and envelope forming an oscillatory circuit, an extension of said envelope forming beyond the region housing said set of electrodes a chamber having a length equal to an odd multiple of the quarter wave length of the length to be generated, and leads for said electrodes extending substantially axially of said envelope and through said chamber, the region of the tube housing said set of electrodes and the chamber having duct communication, the leads passing through said ducts.
5. An ultra high frequency electron tube comprising a metallic envelope housing a set of electrodes including a thermionic cathode, said electrodes and envelope forming an oscillatory circuit, an extension of said envelope forming beyond the region housing said set of electrodes a chamber having a length equal to an odd multiple of the quarter wave length of the length to be generated, and leads for said electrodes extending substantially axially of said envelope and through said chamber, the region of said tube housing said set of electrodes and said chamber having duct communication, the leads passing through said ducts.
6. An ultra high frequency electron tube comprising a metallic envelope housing a set of electrodes including a thermionic cathode, said electrodes and envelope forming an oscillatory circuit, an extension of said envelope forming beyond the region housing said set of electrodes a chamber having a length equal to an odd multiple of the quarter wave length of the length to be generated, and leads for said electrodes extending substantially axially of said envelope and through said chamber, the chamber providing for the reception of getter materials to be vaporized.

WALTER DÄLLENBACH. 35
